UNITED STATES PATENT OFFICE.

EUGENE M. KENT, OF ROME, NEW YORK, ASSIGNOR OF ONE-THIRD TO FAY T. KENT AND ONE-THIRD TO GORDON E. KENT, BOTH OF ROME, NEW YORK, AND ONE-THIRD TO BERT M. KENT, OF WASHINGTON, DISTRICT OF COLUMBIA.

VACUUM CLEANING-TOOL.

1,060,191.

Specification of Letters Patent. Patented Apr. 29, 1913.

Application filed September 24, 1912. Serial No. 722,141.

To all whom it may concern:

Be it known that I, EUGENE M. KENT, a citizen of the United States, and resident of Rome, county of Oneida, and State of New York, have invented certain new and useful Improvements in Vacuum Cleaning-Tools, of which the following is a specification.

This invention relates to vacuum cleaning apparatus and more particularly to tools for cleaning carpets, rugs, etc.

Some of the objects of the invention are to provide a tool adapted to permit a more or less uniform flow of air, and in which the nap of the carpet, through which the air is passing, is perfectly free and not held down by the tool, so that the air will agitate the nap and so loosen and lift the fibers thereof that it can penetrate to the warp with sufficient force to remove any dirt or dust which may have accumulated thereon.

Another object of the invention is to provide an improved cleaning tool having a shoe in engagement with the surface to be cleaned and adapted to permit the body or casing of the tool to be rocked, as it is moved over the surface being cleaned, without affecting the cleaning efficiency of the tool.

Other objects and the features of novelty will be apparent from the following description taken in connection with the accompanying drawings wherein are illustrated various practical embodiments of the invention.

In the drawings: Figure 1 is a perspective view of the preferred form of tool; Fig. 2 is a central vertical section of the same; Fig. 3 is a plan view of the shoe shown in Figs. 1 and 2; and Fig. 4 is a fragmentary view similar to Fig. 2 and showing another form of the invention.

Referring to Figs. 1, 2 and 3, 10 indicates the usual elongated casing or body having an air inlet 11, in the lower side thereof adjacent the surface to be cleaned. A suction pipe or tube 12 is connected with the upper part of the casing in any suitable manner as by the threaded collar 13, this collar permitting the casing to swivel or oscillate on the pipe as the tool is moved to and fro over the surface to be cleaned.

A rectangular shoe 14 surrounds the lower end of the casing 10 and is secured

thereto at its ends by pivots 15, thereby permitting the casing to be rocked vertically relative to the shoe as the tool is moved. The pivots 15 are preferably arranged directly above the lower edge 16 of the front wall of the casing so that this edge will be moved substantially parallel with the surface on which the tool rests, when the casing 10 is rocked. The shoe 14 rests on the carpet or surface to be cleaned, as clearly shown in Fig. 2, and supports the casing 10 with the lower side of the latter slightly above the carpet or surface. The exterior of the rear wall of the casing is curved on a radius from the axis of the pivots 15, as shown at 17, and the inner surface of the adjacent side of the shoe 14 is correspondingly formed to provide a sliding joint between the shoe and the casing at this point. The front side of the shoe is spaced from the casing to provide a downwardly directed air inlet 18 which extends the full length of the casing. This air inlet may be of any suitable cross-section, but is preferably as shown in Fig. 2 so that the flow of air therethrough will not be affected by rocking the casing 10 relative to the shoe.

In the operation of the tool it is moved over the carpet or surface to be cleaned and the air, being drawn through the inlet 18, into the interior of the casing 10, by the suction in the pipe 12, will be projected with considerable force against the surface being cleaned, directly below the inlet 11 and the front wall of the casing, and thoroughly scour the surface and carry away the dirt therefrom. When the tool is used on a carpet or rug having a nap or pile as indicated in Fig. 2, the distance between the front and rear sides of the shoe permits the nap under the casing 10 to be free so that the current of air through the inlet 18 in striking the carpet will penetrate to the warp thereof and lift up the nap and so loosen and agitate it that the dirt clinging thereto will be removed and the dirt accumulated on the warp may be readily carried up through the nap by the air. As the tool moves over the carpet the rear side of the shoe smooths out the nap and the carpet is given a bright sleek appearance.

In the modification shown in Fig. 4, the casing 27 has a shoe 26 pivoted thereto, at the ends of the casing and with the front

and rear longitudinally extending portions spaced from the front and rear walls of the casing to provide the air inlets 28 and 29, these inlets being similar in function to the inlet 18, shown in Fig. 2. It will be observed that the inlets 28 and 29 are in downwardly converging relation so that the streams of air which enter through these inlets will be directed beneath the longitudinal edges of the casing and unite in the casing inlet, and therefore, the tool will be equally effective when moved in either direction.

Having thus described my invention, what I claim is:—

1. In a vacuum cleaning tool, a casing having a long narrow inlet, at the bottom thereof, and a suction pipe connection, means pivoted at the ends of the casing and adapted to engage the surface to be cleaned and support the lower edges of the longitudinal walls of the casing above said surface to permit the casing to be rocked and to provide a free passage for air under the lower edge of one of said walls, and means movably fitting the other of the longitudinal walls of the casing and engaging said surface to prevent air from passing through the space between the lower edge of the said wall and said surface to said inlet.
2. In a vacuum cleaning tool, an elongated casing having a long narrow inlet in the lower side thereof and a suction pipe connection, means pivoted to said casing and having portions arranged substantially parallel with said inlet, on opposite sides of the latter, adapted to engage the surface to be cleaned and support the lower edges of the casing and said inlet above said surface, and there being provided an air inlet along the inner side of one of said portions adapted to direct a current of air downwardly against said surface and below the lower edge of the casing.
3. In a vacuum cleaning tool, an elongated casing having a long narrow inlet in the lower side thereof and a suction pipe connection, a shoe surrounding the lower end of said casing and pivoted thereto and having portions arranged substantially parallel with said inlet, on opposite sides of

the latter, adapted to engage the surface to be cleaned and support the lower edges of said casing and said inlet above said surface, and an air inlet being provided between one of said portions and a wall of said casing adapted to direct a current of air downwardly against said surface and below the lower edge of the casing.

4. In a vacuum cleaning tool, an elongated casing having a long narrow inlet in the lower side thereof and a suction pipe connection, a shoe surrounding the lower end of said casing and pivoted thereto at its ends and having portions arranged substantially parallel with said inlet, on opposite sides of the latter, adapted to engage the surface to be cleaned and support the lower edges of said casing and said inlet above said surface, and there being provided an inlet between one of said portions and a wall of said casing adapted to direct a current of air downwardly against said surface and below the lower edge of said wall, the other of said portions closely fitting a wall of said casing.

5. In a vacuum cleaning tool, an elongated casing having a long narrow inlet in the lower side thereof and a suction pipe connection, a shoe surrounding the lower end of said casing and pivoted thereto at its ends over the lower edge of one wall of the casing and having portions arranged substantially parallel with said inlet, on opposite sides of the latter, adapted to engage the surface to be cleaned and support the lower edges of said casing and said inlet above said surface, and there being provided a downwardly tapering air inlet between one of said portions and said wall adapted to direct a current of air downwardly against said surface and below the lower edge of said wall to said casing inlet, the other of said portions closely fitting the wall of said casing on the opposite side of said casing from said first mentioned wall.

In testimony whereof I affix my signature in presence of two witnesses.

EUGENE M. KENT.
